UNITED STATES PATENT OFFICE.

JOHN J. FLOYD, OF BOSTON, MASSACHUSETTS.

ELECTROTYPE-LOCKING APPARATUS.

No. 865,581.

Specification of Letters Patent.

Patented Sept. 10, 1907.

Application filed 1, 1907. Serial No. 371,361.

To all whom it may concern:

Be it known that I, JOHN J. FLOYD, a citizen of the United States, residing in Boston, county of Suffolk, and State of Massachusetts, have invented an Improvement in Electrotype-Locking Apparatus, of which the following description, in connection with the accompanying drawing, is a specification, like letters on the drawing representing like parts.

In printing from electrotype plates the plates must be securely fastened to a plate carrier or block adapted to be held in whatever form of press used. It is essential, to insure good printing, that the plates be held firmly and be capable of being adjusted accurately to so called hair lines. To provide for holding and adjusting such plates I have provided means which I will hereinafter more fully describe, the particular features of my invention being set forth in the claims at the end of this specification.

Figure 1 is a plan view of a block and plate shown confined to the block by two of my novel locking devices or catches; Fig. 2 is a partial section in the line z , Fig. 1, showing the tool employed to manipulate the locking device; Fig. 3 is a like view with the parts in a different position; Fig. 4 is a section of Fig. 2 in the line z' ; Fig. 5 is a section of Fig. 3 in the line z' ; Fig. 6 is a detail showing the notched shells and springs acting normally to contract the same; Fig. 7 is a detail showing the shells in side elevation.

The block A of metal is bored transversely and lengthwise as at A' and the circular bore holes are slotted, as shown at A^2 , the slits opening in the top of the block. The bore holes, any number of which may be used, are each cut, as shown at A^3 to present a series of teeth or holding notches.

The locking device or catch B , any desired number of which may be used, that depending on the size of the electrotype plate C , six or more such devices being commonly employed with each plate, is fitted into the circular bores A' . The locking devices are all alike, so I need particularly to describe but one of them. The locking device B comprises essentially a body having depending ears d bored for the reception of an expanding bolt D , the latter having its head B' provided with an annular groove b' at one side of which is a stop collar b^2 that is normally held against one of the lugs of the body by a spring b^3 , the outer end of which abuts a nut b^4 screwed onto the threaded end of the bolt. The inner end of this spring abuts a depending portion e of an adjustable plate e' having a plate engaging portion e^3 slotted at e^2 , to receive a pin e^4 rising from the body, the depending portion e acted upon by the spring being held normally in the position shown in Fig. 2, the spring also serving normally to hold the bolt in the position Fig. 2.

Between the ears d , d of locking device B are located two shells f , f one of which is shown externally in Fig. 7,

each shell being concavo-convex in cross section and provided near its opposite ends with a series of teeth 2 , and a space 3 shown best in Fig. 7. In the space 3 I apply a steel spring 4 that acts normally to contract the shells when the bolt is in the position Figs. 3 and 5, thus withdrawing the teeth of the shells from the teeth A^3 of the bores in the block. The body of the locking device has a lip B^4 that is projected through one of the grooves b' so as to serve as holding means for the portion 60 of the electrotype plate C to be held in adjusted position by the locking device, but preferably the lip B^4 will not directly engage the electrotype plate, but rather the edge of the plate will be engaged by the edge e^2 of the plate e' before described, which plate may be 65 adjusted on the locking device B to provide for hair-line adjustments of the electrotype plate.

It will be understood that the device e' is movable longitudinally of the body of the catch B and to secure a very fine adjustment, finer than could be gotten by 75 the teeth of the shell engaging the teeth of the bore in the block, I may insert between the lip e^2 and the undercut portion of the projection B^4 a thin piece of paper or shim of metal to thereby lengthen, as it were, the holding projection B^4 that the end of the projection 80 may be brought into any desired position to form a holding device for the electrotype.

To adjust the catch, I insert the lower prong h of a tool H comprising a shank with a handle h' in an abutment h^2 . In using the tool, I insert the prong h through 85 one of the slots A^2 into the annular groove b' of the bolt, and with the abutment h^2 resting on the projection B^4 of the catch, I tip the tool in the direction of the arrow Fig. 2, withdrawing the bolt and compressing the spring b^3 . The withdrawal of the bolt brings portions of the 90 bolt of smaller diameter between the projections 10 of the shell so that the spring 4 acting normally may contract the shells, withdrawing their teeth from the teeth A^3 cut in the bores of the block, and with the tool yet in the position stated the carriage may be slid in either 95 direction, the withdrawing of the tool permitting the spring b^3 to act and move the bolt from the position Fig. 3 into the position Fig. 2, thus expanding the shells from the position shown in Fig. 5 into the position shown in Fig. 4, where said teeth engage the teeth A^3 100 of the bores.

The construction above described constitutes a self-acting and self-locking catch for as soon as the tool is removed after having adjusted the catch, the shells are expanded automatically to bring the teeth thereon into 105 engagement with the teeth of the plug, thus locking the catch in its adjusted position.

Having described my invention, what I claim as new and desire to secure by Letters Patent is:—

1. In apparatus of the class described, a block having 110 crossing grooves provided with teeth, combined with a plate locking device including separable toothed shells, and

- means to cause the teeth of said shells to engage the teeth of the block.
2. In apparatus of the class described, a block having crossing grooves provided with teeth, combined with a plate locking device including a body, toothed shells, and a device to move said shells one toward the other to effect the disengagement of the teeth of the shells from the teeth of the block.
3. In apparatus of the class described, a block having crossing grooves provided with teeth, combined with a plate locking device including a body, toothed shells, a device to move said shells outwardly that their teeth may engage the teeth of the block, and means acting normally to contract the shells.
- 10 4. In apparatus of the class described, a grooved block and a locking device having a projecting portion exposed at the top of said block, combined with a plate-engaging device carried by the locking device and movable longitudinally thereon, and means to move said plate-engaging device on said locking device to provide for hair-line adjustments of a stereotype plate on said block.
- 15 5. In apparatus of the class described, a plate locking device comprising a body having a plate-positioning projection, a cam bolt, two shells, a spring to move said bolt in a direction and normally hold the same in a position 25 to move the shells away one from the other.
6. In apparatus of the class described, a plate locking device comprising a body having a plate-positioning projection, a cam bolt, two shells, a spring to move said bolt in a direction and normally hold the same in a position 30 to move the shells away one from the other, a spring encircling said shells and moving the same one toward the other and said bolt when the latter is held outwardly in its inoperative position.
- 35 In testimony whereof, I have signed my name to this specification, in the presence of two subscribing witnesses.

JOHN J. FLOYD.
